CLAIM

The ornamental design for a geometric design template as shown and described.

DESCRIPTION

FIG. 1 is a perspective view of a geometric design template, showing my new design;

FIG. 2 is a top view of a geometric design template;

FIG. 3 is a bottom view of a geometric design template;

FIG. 4 is a left side view of a geometric design template;

FIG. 5 is a right side view of a geometric design template;

FIG. 6 is a rear view of a geometric design template; and,

FIG. 7 is a front view of a geometric design template.

1 Claim, 5 Drawing Sheets
